US00D874748S

(12) **United States Design Patent** (10) **Patent No.:** **US D874,748 S**
(45) **Date of Patent:** **** Feb. 4, 2020**

(54) **SPIKE BALL**

(71) Applicant: **Gramercy Products, Inc.**, Secaucus, NJ (US)

(72) Inventor: **William Steinkraus**, Fort Lee, NJ (US)

(73) Assignee: **GRAMERCY ProDucts, INC.**, Secaucus, NJ (US)

(**) Term: **15 Years**

(21) Appl. No.: **29/656,977**

(22) Filed: **Jul. 18, 2018**

Related U.S. Application Data

(62) Division of application No. 29/642,883, filed on Apr. 3, 2018, now Pat. No. Des. 839,497.
